CARTON UNLOADER FOR CONTAINERS

Edward H. Lorenz and Thomas Waugh, West Hartford, Conn., assignors to Emhart Manufacturing Company, Hartford, Conn., a corporation of Delaware

Application July 6, 1951, Serial No. 235,442

10 Claims. (Cl. 214—309)

1

This invention relates to improvements in apparatuses for removing articles, e. g., containers, from their cartons or cases and more particularly to a carton unloader which is particularly designed and adapted to extract a plurality of rows of empty cans or the like from their case or carton as a group and to transfer them to a spaced suitable conveyor or other supporting surface.

Articles such as empty cans may be packed in a carton so tightly that considerable force must be exerted in the direction of their axes to extract them and there is very little space around the individual cans for entry of tongs or the like for gripping them. When this condition exists, prior devices which are designed to operate by stripping the cartons from the articles, either upwardly in the case of inverted cartons or downwardly when the cartons are upright, while the articles are constrained to follow a horizontal path of movement are not satisfactory.

Other prior devices are designed to operate by moving grippers vertically downward into gripping engagement with the upper ends of the articles in an upright case or carton at an unloading station and then lifting the engaged articles vertically upward from the case or carton along the path of descent of the grippers. These necessarily require intermittency of operation so as to be undesirably slow.

An object of the invention is to provide operable pendant grippers on a continuously moving conveyor mounted and operated firmly to engage and to remove as a group all the articles, such as cans, which fill an open-top carton at an unloading station and are packed therein in a plurality of parallel rows, each containing a plurality of the articles.

Another object of the present invention is to provide a carton unloading apparatus which will remove tightly, as well as more loosely, packed upright cans or similar articles from their carton positively and quickly.

A further object of the invention is to provide a carton unloading apparatus of the character described having means carried by a continuously moving conveyor for engaging the upper ends of the individual articles, such as empty cans, disposed in a plurality of rows and fitting tightly in a carton, and for positively extracting these articles from their carton without harmful pressure on or marring of the internal surfaces of the articles.

A still further object of the invention is to provide a carton unloading apparatus having a continuously moving conveyor carrying one or more spaced multiple article removing units, each comprising article upper end-engaging devices corresponding in number and relative arrangement with the articles in a carton to be unloaded

2

and constructed and arranged to engage the upper ends of such articles without interference with one another, despite tight association of the articles in the carton and necessary restriction of relative lateral movements between movable parts of adjacent article engaging devices.

Other objects and advantages of the invention hereinafter will be pointed out or will become obvious from the following description of a practical embodiment of the invention, as shown in the accompanying drawings, in which:

Fig. 1 is a longitudinal vertical section of the novel carton unloader approximately along the line 1—1 of Fig. 2, some elements of the supporting structure being partially broken away;

Fig. 2 is a plan view of the carton unloader;

Fig. 3 is a relatively enlarged side elevation of one of the multiple article removing units of the apparatus;

Fig. 4 is a plan section along the line 4—4 of Fig. 3 of the article engaging devices of said unit, positioned above a carton which is shown in dot-and-dash lines;

Figs. 5 and 6 are fragmentary detail side elevations, each at a right angle with the other, of one of the article engaging devices;

Fig. 7 is a partial plan view of the means for positioning and movably supporting a filled carton at an unloading station with the carton at its initial or spotted position, the view also showing hold down means for certain of the flaps of the carton;

Fig. 8 is a partial view like a right-hand portion of Fig. 7, showing the carton at a more advanced position along its supporting means and the right hand flap hold down means at the position then occupied;

Fig. 9 is a view like Fig. 8 showing the carton of the preceding view at a further advanced position and a second carton approaching the initial or spotted position of Fig. 7;

Fig. 10 is an elevation of the carton with a portion of its side wall broken away and one of the cans therein shown in section, the view illustrating the engagement of the article engaging devices with individual cans in the carton; and

Fig. 11 is a schematic perspective view showing the two transversely spaced paralleled chains of the unloader conveyor together with a transverse carrier plate interposed between and attached to these chains so as always to be maintained horizontal during movement by the chains and showing stationary guides for the chains and the plate, additional positions of the plate during a cycle of the unloader conveyor being indicated by dot-and-dash line showings of the projecting elements at the ends of the plate.

Generally and briefly described, the carton unloader of the invention comprises a rectangular frame structure 1, Figs. 1, 2 and 11, sup-

ported at a predetermined desirable height above a factory floor or the like (not shown) by four uprights 2. Mounted within frame structure 1 is an unloader conveyor, generally designated 3, comprising a pair of transversely spaced staggered endless chains 4 and 5, respectively, lying in parallel vertical planes and carrying a plurality of spaced multiple article removal units 6, Figs. 1 and 2. Each unit 6 comprises a horizontally disposed carrier plate 7 having fixed rigid laterally projecting attaching strips 8 and 9, respectively, at two diagonally opposite corners thereof. See Figs. 2 and 11. Strip 8 is pivotally connected at its terminal end at 8a to a reinforced portion 5a of the chain 5 while the attaching strip 9 is similarly fastened at 9a to a similarly reinforced corresponding portion 4a of the chain 4. The other two diagonally opposite corners of each plate 7 are provided with projecting rigid strips 10 and 11, respectively, carrying projecting rollers 12 and 13, respectively, at their extremities which are free from the conveyor chains. The chains are mounted and operated to move in unison along paths lying in parallel vertical planes so that the portions of the two chains to which two diagonally opposite corner portions of each plate 7 respectively are pivotally attached will always be at the same level, each with the other, and the plate thus will be carried in a constantly horizontal position by the chains throughout a complete cycle of movements of the conveyor. Suitable stationary guides for stretches of the chains and for co-action with the plate-carried rollers 12 and 13, respectively, may be provided, as later explained, to aid in keeping each plate horizontal and in stabilizing its movements by the conveyor chains.

Depending from the plate 7 of each unit 6 are article-engaging devices 14, 14a corresponding in number and relative arrangement with the articles in a carton to be unloaded, e. g., the cans 15 in a carton 16, Fig. 9, when that carton is disposed at an unloading station A on a carton positioning and supporting structure 17 located beneath the path of movement of a unit 6 as shown in Fig. 1. In that view, movement of the conveyor chains in a clockwise direction along their paths has brought the set of article engaging devices 14, 14a of a unit 6 to a position directly over the cans (not shown) in the carton 16 at the unloading station A. That unit 6 includes a pair of depending rigid pusher bars 18, Figs. 1 and 3, which press against the trailing ends of the carton side flaps. See Figs. 4, 7 and 10 also. Further movement of the unloader conveyor will cause the carton 16 on the supporting structure 17, Figs. 1 and 7, to move forward in register with the overlying unit 6 which is also lowered so that its article engaging devices 14, 14a descend into the carton and engage the individual cans therein as indicated by Fig. 10 and as herein-after will be more particularly described. The unit 6 then will be raised as the paths of the connected portions of the conveyor chains turn upward. The cans engaged by the devices 14, 14a of that unit will be lifted as a group from their carton and carried in suspension from the unit as shown for the unit 6 and supported cans 15 at about the middle of the lower portion of Fig. 1. The empty carton 16 will in the meantime have been pushed into a downwardly inclined extension 17a of the carton supporting structure. Further progress of the unit 6 and the cans carried thereby on the lower run of the con-

veyor Fig. 1, will bring them to a position over a horizontal article take-away conveyor 19 as shown in the lower part of the left hand portion of Fig. 1. The article engaging devices 14, 14a of the unit then will be actuated as hereinafter explained to deliver the cans 15 onto the conveyor 19 for transport thereby as indicated for the cans 15 at the extreme left hand end of Fig. 1.

Details of the structure and operation thus generally described will now be given.

Referring again to Figs. 1, 2 and 11, the frame-structure 1 comprises vertically spaced longitudinal side members 20, vertically spaced end members 21, and vertical corner members 22 assembled and rigidly connected together in any suitably known manner. The supporting uprights 2 are rigidly attached to the frame structure 1 adjacent to its corners.

The chain 5 of the unloader conveyor 3 is trained about a front sprocket 23, a rear sprocket 24 and an intermediate upper sprocket 25 and on its lower run passes over an intermediate lower sprocket 26. The rear sprocket 24 is mounted on a short horizontal fixed shaft 27, Figs. 1 and 11, projecting inwardly from a holder 28, Fig. 2, on the far side of the frame structure 1 as viewed in Figs. 1 and 11.

The sprockets 23, 25 and 26 are mounted on short horizontal studs 29, 30 and 31 respectively, parallel with one another and with shaft 27 and similarly mounted in holders on the far side of the frame structure, such holders being indicated at 32, 33 and 34, respectively, in Fig. 2.

The chain 4 is at the near side of the apparatus as viewed in Figs. 1 and 11 and is trained about a front sprocket 35, a rear sprocket 36, and an upper intermediate sprocket 37 and on its lower run passes over a lower intermediate sprocket 38. These sprockets are mounted on parallel fixed short shafts 39, 40, 41 and 42, respectively, projecting from holders 43, 44, 45 and 46, respectively, Fig. 2, mounted on the near side of the frame structure.

It will be observed that the front sprockets 23 and 35 are located at a lower level than the rear sprockets 24 and 36. The upper intermediate sprockets 25 and 37 are located at a level such that the portions 5b and 4b of the chains 5 and 4, respectively, stretching between these sprockets and the rear sprockets are horizontal while the portions 5c and 4c, respectively, of the chains stretching between them and the front sprockets 23 and 35 are downwardly inclined. Similarly, the lower intermediate sprockets 26 and 38, over which the chains pass are located at a level such in respect to the front sprockets 23 and 35 and to the rear sprockets 24 and 36 that the chains move along upwardly inclined paths at 5d and 4d, respectively, on rounding the front sprockets and travelling to the lower intermediate sprockets and then horizontally at 5e and 4e, respectively, from the latter to the rear sprockets. Each unit 6 carried by the chains will be lowered to the lowest point along its path when the chains are travelling in a clockwise direction as viewed in Fig. 1 and the portions of the chains to which the plate 7 of that unit is pivotally attached are at the bottoms of their paths around the front sprockets 23 and 35. As previously stated, the article engaging devices of that unit will have been lowered into engagement with cans in a carton 16 moving on the carton support 17 directly beneath it by the time the unit reaches the lowest level of its travel. Thereafter, the unit

6 and the articles engaged by its article-engaging devices will be raised as the unit supporting portions of the chains complete their travel around the front sprockets and move upwardly along their inclined paths toward the intermediate supporting sprockets 26 and 38.

The axes of the article-engaging devices of the unit will be kept vertical during all movements of the unit by its carrying chains.

The conveyor drive comprises a motor 47 on a cross supporting shelf 48 mounted on the frame structure 1, Figs. 1 and 2. Motor 47 has a driving connection at 49 with a speed reduction unit 50. The latter also is mounted on the same supporting shelf 48 and has a driven shaft 51, Fig. 2, connected by a chain and sprocket transmission 52 with a countershaft 53. The latter extends transversely across the frame structure 1 and may be journaled at its ends in suitable bearings 54, Fig. 2 carried by uprights 55 on the opposite sides of the frame structure. See Fig. 1 also. The countershaft 53 drives the rear sprocket 36 by a suitable chain and sprocket transmission indicated at 56, Figs. 1 and 2. The rear sprocket 24 for the chain 5 is similarly driven from the countershaft 53 by a chain and sprocket transmission 57.

Fig. 11 illustrates the manner in which the carrier plate 7 of a unit 6 is maintained horizontal during its entire cycle of movements. Only the plate 7 of one such unit is shown in this view, the others being omitted for the sake of simplicity and clarity. This plate is shown in full lines in a position near the end of the lower run of its path of movement. The portion of the chain 5 to which the attaching end strip 8 of the plate 7 is pivotally attached is just starting to move from a stationary horizontal guide rail 58 upward around the rear sprocket 24. At this time, the roller 12 at the same end of the plate 7 is starting to move from its course between vertically spaced horizontal portions 59a and 60a of upper and lower stationary guide rails 59 and 60, respectively, upward between arcuately curved portions 59b and 60b, respectively, of these same guide rails. At this time, the roller 13 at the near end of the plate 7 is moving in the air while the portion of the chain 4 to which the attaching end strip 9 is pivotally attached is beginning to move upwardly around a portion (not shown) of the rear sprocket 36. The curvature of the guide rail portions 59b and 60b corresponds to that of the chain-engaging peripheral portions of the sprockets 24 and 36 so that the plate 7 will be maintained horizontal while the portions of the chains attached thereto are passing upwardly around these sprockets.

On rounding the sprocket 24, the portion of the chain 5 to which the attaching bar 8 is connected will be horizontal and it may be supported and guided by a stationary horizontal guide rail 61 during part of its travel to the upper intermediate sprocket 25. Meanwhile, the roller 12 will pass underneath and along the under surface of a stationary guide rail 62. The roller 13 projecting from the near end of the plate will be moved through the air upwardly along an arcuate path at the inner side of the sprocket 36 as the portion of the chain 4 to which the attaching strip 9 is pivotally attached rounds that sprocket. Thereafter, the roller 13 will be moved horizontally in free air until it passes beneath and rides along the under surface of a stationary horizontal rail 63. Meanwhile, the portion of the chain 4 to which the strip 9 is attached will move

along the upper surface of a stationary horizontal guide rail 64. Fragmentary portions of the strips 8 and 9, respectively, of a carrier plate (not shown) are shown by dot-and-dash lines near the middle of the upper part of Fig. 11. At this time, the rollers 12 and 13 carried by the same plate will be riding under the stationary rails 62 and 63, respectively at the positions shown by dot-and-dash lines. After passing over the sprockets 25 and 37, respectively, the portions of the chains 5 and 4 to which these strips 8 and 9 are attached will be moved along downwardly inclined paths to the front sprockets 23 and 35, respectively. On rounding the sprockets 23 and 15 35, these portions of the chains 5 and 4 to which the strips 8 and 9, respectively, are attached will move between vertically spaced stationary inclined guide rails 64, 65 and 66, 67, respectively. When the strip 9 is rounding the sprocket 35, 20 the roller 13 carried by the same plate will be moving along a guide slot between arcuately curved upper and lower stationary guide rails 68 and 69, respectively. This condition is indicated by a dot-and-dash line showing of a strip 9 and 25 a roller 13 in the lower part of Fig. 11. At this time, the roller 12 and the strip 8 at the far end of the same plate will be at the positions also indicated by dot-and-dash lines in the middle of Fig. 11. Thereafter, the roller 12 will be guided 30 between vertically spaced inclined stationary guide rails 70 and 71 onto the upper surface of the horizontal portion 60a of guide rail 60 while the portion of the chain to which the strip 8 is attached passes up the inclined way between the guide rails 64 and 65, over sprocket 26 and then 35 between vertically spaced horizontal stationary guide rails 72 and 58. The portion of the chain 4 to which the strip 9 of the same plate is attached will move meanwhile between the inclined 40 stationary guide rails 66 and 67, over the sprocket 38 and then between vertically spaced stationary horizontal guide rails 74 and 75, respectively. The roller 13 of the same plate will be moved at 45 this time through the air until it encounters the upper surface of an inclined stationary guide rail 76 by which it will be guided for a distance on the way to the position shown in full lines in Fig. 11.

Referring now to Figs. 3, 5 and 6, it will be noted that each article engaging device 14 of a unit 6 comprises a vertically disposed tubular body member 77 securely fastened against the under side of its plate 7, as by cap screws 78, Fig. 6, in axial alignment with a vertical opening 79 in the plate 7, Fig. 5, this for a purpose presently to be described. The body 77 is provided with a plurality of vertical slots 80 through its wall, there being two diametrically opposite such slots in the example shown as appears from Fig. 5. Cooperative hanging rigid tong or gripper arms 81 have their upper portions disposed in these slots and pivotally attached to the body member 77 by horizontal pivot pins 82 spanning the slots. These tong or gripper arms have inwardly projecting hooks or bills 81a at their lower free extremities. They also have inwardly extending integral arms 81b extending from their pivoted upper portions into and toward the vertical center line of an axial space or chamber 83 in the body member 77. The inner ends of these actuating arms bear against the lower end of a plunger 84 which extends downwardly through the opening 79 in the plate 7 into the chamber 83. A compressed coil spring 85 in the chamber 70 83 rests upon the floor of that chamber and is

surmounted by a disc 86 which it presses against the under sides of the actuating arms 81b of the tong members so as to tend to raise these arms as far as possible. This, of course, tends to swing the lower hooked ends of the hanging tong or gripper arms 81 toward each other.

An axially bored centering taper plug or inverted cone 87 is slidable on a tubular member 88 which depends from the body 77 in axial alignment therewith. Member 88 may be integral with the body 77 or a separate element which is held firmly pressed against the bottom of the member 77 by a supporting bolt 89 and a washer 90 interposed between the bolt head and lower end of tubular member 88, the shank of the bolt extending through the bolt hole 91 in the bottom of the body member 77 and being engaged by a nut 92 located in the body member chamber 83. The washer 90 is sufficiently larger in diameter than the lower end of tubular member 88 to underlie the bottom of the centering taper plug 87 sufficiently to support the latter on the member 88 when it is at the lower limit of its vertical sliding movement on such member. A vertical guide pin 93 projects upwardly from the centering taper plug 87 into a vertical guide slot or opening 94, Fig. 3, in the lower end portion of the body member 77 so as to prevent independent turning of the centering taper plug about its vertical axis. The plug 87 may limit the inward or closing swinging movements of the hanging tong or gripper arms 81. Such plug may be a hollow shell made of chromium plated metal or other suitable material and provided with an integrally formed central hub or internal sleeve portion 95 fitting slidably on the supporting tubular member 88.

Each article engaging device as just described is identical with every other one of a unit 6 except that the outer tong arms 81 may be omitted from the devices at two diagonally opposite corners of a rectangular group comprising four of these article engaging devices per row in one direction and six such devices per row in a direction at a right angle therewith, as shown in Fig. 4. This arrangement provides article-engaging devices of the same number and the same relative positioning as the cans 15, Fig. 7, in a carton 16 to be unloaded. The two diagonally opposite corner devices 14 from which the outer tong arms are omitted are marked 14a and appear to advantage, in Fig. 4. Corner devices 14a also appear in Figs. 3 and 10. It will be clear from Fig. 4 that the omission of tong arms from these two corner devices is to enable lowering of the entire set of article engaging devices of a unit sufficiently into an underneath carton to engage the upper ends of all the twenty-four cans therein and that, without such omission, the corner tongs would strike the top or catch on the outer wall of the carton. The corner cans engaged by these single tong-arm corner devices will be lifted with the other cans since their contact with the adjacent cans as the entire assembly is raised will keep them engaged with the single tong arms until such arms are opened in unison with the other tong arms, as presently will be described. It will be understood that the carrier plate 7 of each unit is of approximate width and length to permit attachment of the requisite number of article-engaging devices to the under side thereof with the individual devices suitably spaced and relatively arranged according to the spacing and relative arrangement of the cans in the carton to be unloaded and individually pre-

set angularly about their respective vertical axes to obviate interference between adjacent tong arms. See Fig. 4.

The tong members 81 of the article-engaging devices are spring pressed continuously toward closed position by means hereinbefore described. As the carrier plate 7 with these devices dependent therefrom is moved downward into the waiting carton at the unloading station, the centering plugs 87 enter the open upper ends of the cans and may ride upward on their supporting members 88 by reason of their contact with the rims of the cans while the unit 6 as a whole is still moving downward. The free, hooked lower ends of the tong arms will slide downward over the rim beads 15a of the cans and snap closed beneath such beads. The engaged positions of some of these article-engaging devices with cans in the carton are shown by Fig. 10. The cans are close together in the carton as indicated and to prevent interference between adjacent centering plugs, the upper portions of these plugs may be partially cut away or formed with flat portions 87a. The outer surface of the plug is in contact between the cut-away or flat side portions 87a with the internal surface of the can at its rim and centers the can properly for the tongs. This contact is very light, being substantially a line contact when the can is truly cylindrical and of standard dimensions. The light contact is advantageous in preventing marring of the internal surface of the can, particularly if such surface is lacquered or otherwise coated and also aids release of the cans when the tongs carrying them are opened. Cans internally bent or distorted somewhat but not to sufficient extent to make them unsuitable for use will be engaged by the article-engaging devices. While the opening and closing movements of the tongs are but slight, the cans fit tightly in the carton and this tends to cause interference between adjacent tong members of adjacent devices. Such interference is obviated by attaching the respective article-engaging devices to their carrying plate in angularly turned positions such that adjacent tong members of adjacent article-engaging devices lie in different vertical planes so that they may open without striking each other. See the showing in dotted lines of open positions of two adjacent tong members 81 in the lower left hand corner portion of Fig. 4. This also aids all outside tongs to clear the walls of the carton.

The plungers 84 are rigid elements carried by a horizontal opening plate 96 which overlies the carrier plate 7 and has outwardly projecting apertured corner ear portions 97 fitting slidably over upstanding fixed studs 98 on the plate 7. See Figs. 2 and 3. Coil springs 99 beneath the ears 97 press washers 100 upwardly against such ears so as to tend to maintain the opening plate 96 raised as far as possible, this being limited by stop nuts 101 on the upper end portion of the studs 98. Screw threaded stop elements 102 depend from the opening plate 96 toward the plate 7 with which they will contact on a predetermined downward movement of the plate 96 to limit the downward working movement of the plate 96. A lever for forcing the plate 96 downward comprises a pair of spaced lever bars 103, Fig. 2, connected at one end by a shaft 104 which is pivoted in fixed bearing blocks 105 on the plate 7. The lever bars 103 are connected intermediately by a cross shaft 106 which extends through apertured upstanding lugs 107 on the

opening plate 96. The lever bars 103 are connected at their free ends by a cross bar 108 which carries spaced rollers 109. During movement of a unit 6 with the articles carried thereby along a lower run of the unloader conveyor, the rollers 109 encounter the under surfaces of yieldable cam levers 110. These are shown in dotted lines in Fig. 2 and one of them is shown in Fig. 1. The lower cam surface of each of these levers is formed as indicated at 111 in Fig. 1 to bias the free end of the opening lever downward so as to depress the opening plate 96 and force the plungers 84 downward in the individual article engaging devices. In consequence, the tongs of such devices will be opened to release the articles carried thereby. This action takes place when the unit 6 is over the article take-away conveyor 19 as hereinbefore has been stated. The cam levers 110 are intermediately pivoted on a stationary cross shaft 110a and tension coil spring means 112 yieldingly urge their forward camming end portions downward to a limit set by contact of their rear portions with stop means 110b, Fig. 1.

The carton supporting and positioning structure 17 comprises a pair of spaced normally horizontal side frame members 113 extending below the front end portion of the frame structure 1 and supported at its front end on a transverse horizontal pivot shaft 114, Fig. 1. The side frame members are connected at intervals by transversely disposed rollers 115, the peripheries of which extend slightly above the level of the upper edges of the side members 113. Coil springs, indicated at 117 in Fig. 1, connect the side members 113 with the main frame structure so as yieldingly to retain the pivoted carton-supporting structure 17-17a in its normal horizontal position, against fixed stops, one of which is shown at 217 in Fig. 7.

The carton 16 containing the articles to be unloaded may be placed in a predetermined position on the rollers 115 by suitable carton feeding means (not shown) or manually. As thus spotted on the structure 17, the front wall of the carton bears against a raised downwardly retractile stop element 118. This is the upturned free end of an angularly shaped arm 119 of lever 120 which is fulcrumed on a transversely disposed shaft 121 extending between the frame members 113. The lever 120 is operable by an upwardly projecting actuating arm 122 connected by a connecting rod 123 with the lower end of a vertically disposed lever 124 which is intermediately fulcrumed on a horizontal shaft 125 carried by a side wall member of the main frame work 1. The upper end of lever 124 carries a cam roller 126 bearing against the periphery of a cam 127 on the sprocket 26. Sprocket 26 makes one revolution per unit 6. Cam 127 is rotated with that sprocket and hence driven in synchronism with the unloader conveyor carrying the article removal units 6. A suitable spring (not shown) may be provided to maintain the cam roller 126 in bearing contact with the periphery of cam 127 if the weight of the connected parts is not sufficient to accomplish this result without the use of such a spring. The cam contour is such that the carton stop 118 will be retracted downwardly at a suitable time in a cycle of operations of the unloader to permit forward movement of the carton along the roll-way of structure 17 under pressure applied thereto by the depending pushers 18 of the particular unit 6 that is then in position to unload such carton. As previously

explained, the forward movement of the carton by pushers 18 will be in register with the assembly of article-engaging devices of the overhead unit 6 as these devices are lowered to their article-engaging positions, this despite the variation of the horizontal speed of the conveyor carrying the units 6. After the articles have been gripped and by the time they have been extracted from the carton, the pushers 18, which depend a considerable distance below the associate article-engaging devices, will have pushed the empty carton from the horizontal series of transverse rollers 115 onto and down an inclined series of transverse rollers 128 which are mounted in a downwardly inclined extension 17a of the carton supporting structure. In lieu of the pushers 18 carried by each unit 6, the contact of the centering plugs 87 of the unit with the cans in the carton being unloaded could be utilized to effect the desired forward movement of the carton. The use of pushers is preferred.

When the cans are set down on the article removal conveyor 19, the plugs of the article-engaging devices involved in their transfer will steady them against the possibility of tipping over and onto the conveyor 19. The conveyor 19 is, of course, driven in synchronism with the unloading conveyor and the plugs will be raised away from the cans shortly after they have been deposited.

The spotted position of a carton at the unloading station may vary slightly either transversely of the carton positioning structure 17 or longitudinally thereof and the taper of the centering plugs of the article-engaging devices will assure accurate centering of usable cans in relation to the attaching devices so that such cans will be firmly gripped and extracted from the carton. If a carton should contain an excessively deformed or squashed can or a can closed at its top, the pressure thereon from the descending unit 6 will depress the forward end of pivoted structure 17 so that the carton and its contents will be discharged from the structure 17 without being unloaded.

The invention provides means to hold down a carton during unloading as well as such of its flaps as require holding down. As shown, Figs. 2 and 7, a fixed horizontal hold down guide 129 is provided at the unloading station A over a side portion of the rollway structure 17 to hold down the end flap 130 of the carton at that side of the rollway. As shown in Fig. 7, the carton is spotted with its side flaps 131 and 132 respectively disposed in leading and trailing positions in relation to the body of the carton and with a second end flap 133 at the opposite side of the rollway from stationary hold-down guide 129. A movable hold down means for the leading side flap 131 and the end flap 133 comprises a pair of cooperative horizontally disposed hold down bars 134 and 135, respectively, the bar 134 being pivoted on a vertical pivot element 136 located at the carton infeed end of the rollway near one corner thereof while the bar 135 is pivoted on a vertical pivot element 137 located at the same side of the rollway but in a more forward location. These arms 134 and 135 have outwardly turned actuating arms 134a and 135a, respectively, connected by a coil spring 138, tending to swing them laterally about their respective pivotal axes toward the longitudinal median line of the rollway. A stop 139 projecting from the arm 134a against a fixed abutment, as one of the uprights 2 as shown in Fig. 7, limits inward swinging movement

of arm 134. A projecting stop element 140 on the inner end of arm 135 bears against a fixed stop element 141 carried by the free end of arm 134 to limit the inward swinging movement of arm 135. A headed stud 142 on the free end of arm 135 works in a slot 143 in a stationary horizontal bracket arm 144 to guide and stabilize the swinging movements of arm 135.

With the arms 134 and 135 in the positions shown in Fig. 7, both the carton end flap 133 and the leading carton side flap 131 are retained in their open, outwardly bent positions. The opposite carton end flap, 130, at the opposite side edge of the rollway is underneath the stationary hold down bar 129. The inner side edge portions of the arms 134 and 135 may at this time extend inwardly beyond the plane of the adjacent end wall of the carton proper. As the carton is moved forward on the rollway by the pushers 18 of the overlying moving units 6, the arm 134 will be swung laterally outward by the contact of its obliquely extending inner side edge 145 with one of moving pushers 18. This will cause outward swinging movement of the arm 135 also, the element 141 carried by the arm 134 transmitting motion to the projection 140 on the adjacent end of the arm 135. The laterally swingable hold down arms thus will be moved out of the way of the descending article-engaging devices of a unit 6. As shown in Fig. 8, the carton has been advanced on the rollway to a position such that the can engaging devices of a unit 6, which are not shown in that view, will have been lowered into engagement with the cans in the carton. On further movement of the carton, the pusher 18 which has been biasing the arm 134 outward passes beyond the free end of that arm and releases it so that it swings inward to position to hold down the leading side flap and the right hand end flap of the next carton in line, as shown in Fig. 9. Meanwhile, the arm 135 is actuated by the pusher 18 and is biased laterally outward so as not to interfere with the upwardly moving cans as they are lifted from the carton. When the pusher 18 passes a little further beyond the position shown in Fig. 9, the arm 135 will be released therefrom and will be returned inwardly by the action of the spring 138 until the projection 140 strikes the stop element 141, the two arms, 134 and 135, respectively then being again in the positions shown in Fig. 7.

When the cans which have been extracted from a carton and carried by the article-engaging devices of a unit 6 to a delivery position over the take-away conveyor 19 are set down on that conveyor, the plugs of the article-engaging devices will steady the deposited cans against the possibility of tipping over and stabilize their positions on the conveyor 19 until such plugs are lifted out of the deposited cans by an upward divergence of the unloader conveyor from the plane of the take-away conveyor. The latter may of course be driven by suitable means, not shown, at the same linear speed as the unloader conveyor.

It will be obvious that apparatus of the invention may be used to engage, transfer and deposit multiple containers and like articles under widely differing conditions and for specifically different purposes. For example, the apparatus may be readily adapted and used to deposit the transferred group of articles in a case or carton or other receptacle rather than on a flat horizontal conveyor and such articles might be picked up from a moving conveyor or similar support in-

stead of from a carton or case. Also, many changes in and modifications of the illustrative apparatus shown in the accompanying drawings and herein particularly described will be obvious to those skilled in the art and we, therefore, do not wish to be limited to the details of such illustrative embodiment of the invention.

I claim:

1. In combination, a continuously moving endless transfer conveyor having a path of movement such that each of successive transverse portions of the conveyor descends to and ascends from a low level position during a cycle of movements thereof, a support extending beneath said low level position and on which a carton open at its top and containing a plurality of upright containers may be placed and be moved rectilinearly along a horizontal path passing directly beneath and beyond said low level position, a plurality of article engaging devices corresponding in number and relative arrangement with the containers in said carton and suspended from a transverse portion of the conveyor so that the axes of the individual devices are vertical at all positions, the containers in said carton being disposed in a plurality of cross rows therein and the article engaging devices likewise being arranged in a plurality of cross rows suspended from the transfer conveyor, said devices being constructed and arranged automatically to supportingly engage upper end portions of the containers in said carton when the portion of the conveyor carrying said devices has descended to said low level position and the carton has been moved on its support to a position directly therebeneath, said devices thereafter acting to lift the containers engaged thereby from the carton as the portion of the conveyor carrying said devices ascends from said low level position to a higher level portion of its path of movement, and carton pushing means carried by said conveyor in position to engage the carton on its support preceding completion of downward movement of the article engaging devices into engagement with the containers in the carton and thereafter to move the carton in register with the article engaging devices during their descent into supporting engagement with the containers in the carton.

2. The combination defined by claim 1 wherein said carton pushing means is moved by said transfer conveyor to propel the carton on its support beyond a position beyond said low level position of the conveyor as the containers are lifted from the carton by the article engaging devices.

3. The combination defined by claim 2 wherein said support for the carton comprises a horizontal portion on which the carton may be moved during lifting of the containers therefrom and a further downwardly inclined portion constituting a slideway for the empty carton.

4. The combination defined by claim 1 wherein the support on which said carton may be placed and moved comprises a normally horizontal structure pivotally supported at its carton infeed end at a predetermined level by a transverse supporting pivot element and yieldingly supported adjacent to its opposite end by spring suspension means, said spring suspension means permitting the support to pivot downwardly under pressure from the article-engaging devices to discharge the carton and its contents from the support should an obstruction in the carton in the path of downward movement of the article-engaging devices prevent full descent of such devices to

their operative article-engaging position in the carton.

5. The combination defined by claim 1 wherein in said support for the carton comprises a normally horizontal structure and, in addition, a normally raised downwardly retractile stop projecting above the carton supporting surface of said structure to spot the carton on the support at a position in advance of the low level position of the transfer conveyor, means operable in synchronism with descent of the article-engaging devices to retract said stop downwardly to permit forward movement of the carton when said devices have been brought to a position above and in register with the containers in the carton, and pusher means operating then to move said carton forward on its support in register with said article-engaging devices.

6. In a multi-article transfer apparatus, a horizontal carrier plate, a plurality of cross rows of article engaging devices depending from the under surface of said horizontal plate, each device comprising a vertical body fixed to the plate, an article centering taper plug carried at the lower end of the body for limited free vertical movements relative to the body, a single pivoted tong member at the inner side of the body of each of the two devices located at diagonally opposite corners of the assembly carried by the plate, a pair of cooperative pivoted tong members carried by the body of each of the other article-engaging devices of the assembly, spring means urging said pivoted tong members to their closed positions, normally raised plungers mounted for limited vertical movement and operative when lowered to actuate said tong members to swing them to their open positions, and means common to all said plungers for actuating them in unison.

7. The combination defined by claim 6 wherein the means to actuate said plungers in unison comprises a vertically movable horizontal opening plate supported above said carrier plate and carrying said plungers, spring means tending to maintain said opening plate raised in relation to the carrier plate, and means for depressing said opening plate to lower said plungers.

8. The combination defined by claim 6 wherein the bodies of the respective article engaging devices are fixed to said carrier plate in preset angularly turned positions so that adjacent pivoted tong members of adjacent article engaging devices open and close in different vertical planes without contact with each other.

9. In a multi-article transfer apparatus, a transfer conveyor comprising a pair of transversely spaced and staggered endless conveyor chains mounted to move along endless paths lying in parallel vertical planes and a transversely disposed, horizontal carrier plate extending between corresponding portions of said chains and attached pivotally thereto solely at two diagonally opposite corner portions thereof so that said plate will remain horizontal during all travel with the conveyor chains, means to drive said chains continuously, a plurality of article engaging devices fixed to and depending from the under surface of said carrier plate in a plurality of cross rows corresponding in number and relative arrangement of components with cross rows of containers in a carton to be unloaded, means to support such a carton with the containers

therein at an unloading station beneath a portion of the path of said plate and so that said carton may be moved horizontally with the plate during the unloading operation, said carton having outwardly turned flaps at the sides and rearwardly and forwardly turned flaps at the rear and front, respectively of its open upper end, stationary hold-down means for the outturned flap at one side of the carton upper end, and laterally swingable, pivoted hold-down means for the flap at the opposite side and the forwardly turned flap at the front of the carton upper end.

10. In a multi-article transfer apparatus, a transfer conveyor comprising a pair of transversely spaced and staggered endless conveyor chains mounted to move along endless paths lying in parallel vertical planes and a transversely disposed, horizontal carrier plate extending between corresponding portions of said chains and attached pivotally thereto solely at two diagonally opposite corner portions thereof so that said plate will remain horizontal during all travel with the conveyor chains, means to drive said chains continuously, a plurality of article engaging devices fixed to and depending from the under surface of said carrier plate in a plurality of cross rows corresponding in number and relative arrangement of components with cross rows of containers in a carton to be unloaded, means to support such a carton with the containers therein at an unloading station beneath a portion of the path of said plate and so that said carton may be moved horizontally with the plate during the unloading operation, said carton having outwardly turned flaps at the sides and rearwardly and forwardly turned flaps at the rear and front, respectively, of its open upper end, stationary hold-down means for the outturned flap at one side of the carton upper end, laterally swingable, pivoted hold-down means for the flap at the opposite side and the forwardly turned flap at the front of the carton upper end, laterally swingable, pivoted hold-down means for the flap at the opposite side and the forwardly turned flap at the front of the carton upper end, and rigid pusher means depending from said carrier plate to engage the carton at its rear when the plate has arrived at a predetermined point along its path and thereafter to move the carton forward on its support in register with said plate during movement of the plate along a further part of its path, said rigid pusher means being operable to swing said movable flap hold-down means laterally outward during this registering movement of the plate and the carton to clear the space above the upper ends of the containers in the carton to permit engagement of said container upper ends by the article-engaging devices carried by the plate.
